UNITED STATES PATENT OFFICE

WALDO W. JENCKES, OF MILFORD, MASSACHUSETTS, ASSIGNOR TO MILFORD SHOE COMPANY, OF MILFORD, MASSACHUSETTS, A CORPORATION OF MASSACHUSETTS.

SHOE.

SPECIFICATION forming part of Letters Patent No. 760,870, dated May 24, 1904.

Application filed January 2, 1904. Serial No. 187,458. (No model.)

To all whom it may concern:

Be it known that I, WALDO W. JENCKES, a citizen of the United States, residing at Milford, in the county of Worcester and State of Massachusetts, have invented an Improvement in Shoes, of which the following description, in connection with the accompanying drawings, is a specification, like letters on the drawings representing like parts.

10 This invention has for its object more particularly the production of a novel inner sole, the heel end of which is composed of a layer of felt inclosed in a pocket and unattached to the heel end of the body of the inner sole, in which body enter the nails usually employed to attach the heel of the shoe to the outer sole, the nails confining the inner sole and the outer sole firmly together.

Figure 1 is a view, partially broken out, of 20 that side of the usual inner sole with which the outer sole contacts. Fig. 2 is a sectional detail in the line α . Fig. 3 is a cross-section in the line α' , Fig. 1, the pocketed heel end of the cushion sock-sole being represented as 25 lying flat on the heel end of the inner sole rather than uplifted, as in Fig. 2; and Fig. 4 is a cross-section of the finished shoe to show the upper, outer, and inner soles, cushion sock-sole, and welt.

30 The inner sole herein shown and embodying my invention comprises a piece of sole-leather A, cut into a sole shape and constituting the body of the inner sole, (see Fig. 1,) said body being channeled from the dotted line y , Fig. 1, which line designates the breast of the heel to be attached to the outer sole, the channel running along both sides of the sole and about the toe end thereof. This channel may be of any usual contour, and 40 after turning back the channel-flap α I apply to the body of the inner sole a sock-sole, to be described, the sock-sole and the body comprising my novel inner sole. This sock-sole is composed, preferably, of a piece or layer of thin leather, which I have designated by the letters b b' , the letter b designating that part of said layer that is to overlap the body and its edge from the toe to the line y , the letter

of reference b' designating the heel end of said layer from and extended to the left of 50 the dotted line y .

A constituent member of the sock-sole is a layer of felt c or other equivalent textile material that will yield somewhat to the shape of the under side of the foot of the wearer of 55 the shoe.

The layer of felt c is shaped substantially to conform in shape and size with the piece of leather A employed for the body of the inner sole; but the layer of leather or material b b' is larger than either the felt or the body A, so that the edges of said layer extend outwardly beyond the edge or outline of the body A.

The portion of the material b and b' extending beyond the width of the body A is designated by dotted lines, Figs. 2, 3, and 4, showing what becomes of this surplus width of the material b b' .

In making the inner sole the felt c , shaped 70 to correspond substantially with the shape of the body A, is laid on that face of the body that is to be uppermost in the shoe, and the layer b b' is then laid onto the top of the felt. It will be noticed that the edges b b' of the thin layer 75 of material of the sock-sole is snipped, to thus provide for infolding said edge about a curved portion of the edge of the body. The extended edge b' (suitable india-rubber cement having been applied in the channel or to the 80 edge) is overturned (see Figs. 1 and 4) into the channel of the body and by pressure is made to adhere to the body and confine the cushion c of felt in place on the sole from the dotted line y forward to the toe of the inner sole. 85

The portion b' of material to be interposed directly between the under side of the heel of the wearer and the heel end of the body A is treated differently—i. e., the surplus b' is inturned on the felt, as represented in Figs. 90 2 and 3, and a facing e , preferably of thin leather and having substantially the shape of an ordinary heel-lift, is cemented, preferably, to the inturned portion b' of the edge, as represented in said Figs. 2 and 3. This construction leaves the layer of felt c at the heel 95

end of the sock-sole inclosed in a pocket and overlying the heel end of the body A of the inner sole, the portion of the felt overlying the heel end of the body being, preferably, 5 left unattached thereto; but yet, owing to the leather forming the outer and inner faces of the pocket embracing the heel end of the felt, the felt is stiffened, so that in wear the heel end of the sock-sole will not curl up or be- 10 come displaced.

Fig. 3 shows an outer sole B applied to the inner sole and with a heel C, represented as composed of but two lifts, the heel being united to the outer sole and inner sole by usual 15 nails D, the inner ends of which are clenched in the heel end of the body A of the inner sole. When so attaching the heel, the pocketed end of the sock-sole will be turned outwardly, so that a piece of metal or any usual anvil may 20 contact with the upper side of the heel end of the body A.

By employing a sock-sole in a pocket and disconnected from the heel end of the body of the inner sole the nails used to attach the 25 heel to the shoe may be upset in the body of the heel end of the inner sole and under no condition can said nails work through and contact with the foot of the wearer of the shoe, for such movement is resisted by the 30 cushion-pocketed heel end of the sock-sole.

Referring to Fig. 4, the upper E is represented as having its edges laid in contact with the inturned edge b^x of the material b, and thereafter a welt w is applied as usual, and 35 the welt, upper, and inner soles are united by a series of stitches d, and the welt is attached to the outer sole by through-and-through stitches e. This figure also shows the usual "between substance" h between the inner 40 sole and the outer sole.

I do not claim, broadly, a cushion inner sole; but I am not aware that a cushion inner sole has ever been so constructed as to leave the

textile material forming part of the cushion inner sole inclosed in a pocket and applying 45 the heel end of the body of the piece of sole-leather employed in the production of the inner sole.

Having described my invention, what I claim, and desire to secure by Letters Patent, 50 is—

1. A leather inner sole, comprising a channeled body and a sock-sole comprising a felt body laid thereon and extended from the heel to the toe end thereof, a layer of thin leather 55 forming the face of the sock-sole and having its edges inturned about and stitched to the channeled flap of the body of the inner sole about the shank and fore part, combined with a facing secured to the heel end of the thin 60 layer of leather comprising part of the sock-sole to form at the heel end thereof a pocket to inclose the heel end of the felt part of the sock-sole thus leaving the sock-sole unattached to the body of the inner sole at the heel end 65 thereof.

2. An inner sole comprising a body channeled and presenting a lip extending about the toe and edge of the sole to the rear of the shank, and a layer of felt of substantially the 70 shape of the body, and a layer of thin leather overlapping the felt, the edges of the layer of thin leather being folded about the edge of the body from the rear of the shank along the sides and about the toe thereof, the felt 75 from the rear of the shank about the heel being inclosed in a pocket substantially such as described and left unattached to the heel end of the inner sole.

In testimony whereof I have signed my name 80 to this specification in the presence of two subscribing witnesses.

WALDO W. JENCKES.
